COIN OPERATED MECHANISM

Charles B. Gilmore, Chicago, Ill., assignor to
O. D. Jennings & Company, Chicago, Ill., a
corporation of Illinois

Application March 6, 1930. Serial No. 433,550

10 Claims. (Cl. 194—1)

This invention relates to a coin control apparatus and has for its object to provide a construction in which simple and novel means in the form of a coin stop, and which is associated 5 with a coin chute, is provided for blocking the normal path of the coins so as to return subsequently deposited coins before the previously deposited coin has affected the operation of suitable vending mechanism associated therewith.

10 Another object of my invention is the provision of means associated with a coin stop to maintain the same in a positive blocking position to prevent spurious tokens from being deposited before the previously deposited coin has affected 15 the mechanism, to maliciously disable the mechanism.

A further object of my invention is to provide a coin stop in association with a coin chute which, upon the insertion of a token therein, is instantaneously moved into blocking position to prevent another token from being deposited should the operator inadvertently insert another token without affecting the operation of the mechanism with the previously deposited coin.

25 A still further object of my invention is to provide spring means associated with the coin stop which is engaged by a deposited coin to move the stop into blocking position to yieldingly hold the coin stop against a face of the coin chute.

30 A still further object of my invention is to provide a spring member on the coin stop which engages a deposited coin to force the same against a face of the coin chute irrespective of the thickness of the coin to yieldingly hold the coin stop in blocking position.

35 A still further object of my invention is to provide a machined face in the coin chute adjacent to the machined edge of the coin stop to provide a substantially perfect metal-to-metal contact when the coin stop is moved into blocking position.

40 With this and other objects in view the invention consists of novel details of construction and arrangement of parts as will be more fully hereinafter disclosed in the ensuing specification and particularly pointed out in the claims.

45 Referring to the drawings forming part of this specification and in which like reference characters designate like parts in the several views:

Fig. 1 is a side elevation, partly in section, of a coin controlled apparatus to which my invention is applied;

50 Fig. 2 is a sectional view on the line 2—2 of Fig. 1, with the apparatus in front elevation;

Fig. 3 is an enlarged detailed view in elevation of the coin chute and its associated parts;

Fig. 4 is a right side elevation of Fig. 3;

Fig. 5 is a horizontal sectional view, taken on the line 5—5 of Fig. 3 and looking in the direction of the arrows; 60

Fig. 6 is a rear view of the lower portion of the coin chute illustrated in Fig. 3;

Fig. 7 is a perspective view of the coin retainer latch associated with the delivery end of 65 the coin chute.

Fig. 8 is an enlarged detailed view in front elevation of a modified form of coin tripping mechanism associated with the coin chute.

Fig. 9 is a right-side elevation of Fig. 8. 70

Fig. 10 is an enlarged detailed view in front elevation of still another modified form of the coin tripping mechanism associated with the coin chute;

Fig. 11 is a right-side elevation of Fig. 10. 75

The present invention can be applied to a vending machine or other coin control apparatus. In the drawings the actuating and coin controlled devices of such an apparatus only are shown. As shown the coin controlled machine or apparatus is arranged within an inclosing casing 1, and the actuating and coin controlling devices are mounted upon an upright bracket 2, fixed within the forward portion of the casing. The main operating lever 3 is mounted on a pivot 4, on one side of the bracket 2 and projects forward through a slot 5 in the casing 1, the forward end of the lever being provided with an operating handle 6. The inner end of the lever 3 is operatively connected by a link 7 to the vending or other means which are to be actuated. The spring 8 connected to the upper portion of the bracket 2 and to the actuating lever 3 holds the latter in its normal position against the stop 9 on the bracket 2. A full stroke ratchet 10, is formed upon the central portion of the lever 3. It is arranged to cooperate with a pivoted, spring retaining pawl 11 on the bracket 2 to compel a complete shift of the lever 3 before it can be returned to its normal position. 80

Fig. 12 is a locking latch for controlling the actuation of the lever 3. It is mounted at its lower end upon a pivot 13 secured to the lower front portion of the bracket 2. The latch extends upwardly on one side of the lever 3 and is provided at its inner edge with a curved or arc shaped portion 14 which terminates at its upper end in a shoulder 15. Above the shoulder, the lever 12 is provided with a rearwardly extending cam portion 16 which is arranged to engage a laterally project- 85

105

110

115

A locking latch 12 for controlling the actuation of the lever 3 is mounted at its lower end upon a pivot 13 secured to the lower front portion of the bracket 2. The latch extends upwardly on one side of the lever 3 and is provided at its inner edge with a curved or arc shaped portion 14 which terminates at its upper end in a shoulder 15. Above the shoulder, the lever 12 is provided with a rearwardly extending cam portion 16 which is arranged to engage a laterally project-

ing lug 17, formed upon the lever 3. A spring 18 is connected at one end to a hook 19 on the upper end of the latch 12 and at its opposite end to a pin secured to the bracket 2. The spring 18 tends to swing the latch 12 rearwardly and holds its rear edge in engagement with the lug 17 of the actuated lever 3. Normally the cam 16 on the latch 12 engages the lug 17 and the latch 12 is then held in the position shown in Fig. 1.

The lever 3 can be depressed to a slight extent without inserting coin, but unless a coin is inserted the spring 18 will move the latch 12 rearwardly as the lever 3 is depressed and, after a slight initial movement of the lever, the lug 17 will thereupon engage the shoulder 15 of the latch 12 thereby arresting the actuating lever and locking the lever 3 against further movement. This slight initial movement of the actuating lever 3 is not sufficient to bring the pawl 11 in engagement with the teeth of the ratchet 10.

The latch 12 is controlled by a lever 20 which is pivotally secured intermediate of its ends by a pivot 21 fixed to the upper front portion of the bracket 2. The lower end of the lever 20 is provided with a pin 22, which projects into a vertical slot 23 formed in the upper end of the latch 12. The upper end of the lever 20 is off-set over the upper portion of the bracket 2 and carries a plunger or finger 24 which is adjustably fixed thereto by a set screw 25; the said finger 24 extending forwardly therefrom toward the coin chute C of the apparatus. As the latch 12 shifts from its normal to its locking position during the initial movement of the actuating lever 3, the upper end of the arm 20 moves forwardly and the finger 24 is forced through a suitable opening formed in the coin chute C. If a coin or token of a predetermined size is inserted into the coin chute C, it will be engaged by the plunger or finger 24 so that the coin and the lever 20 will prevent the shift of the latch 12 to its locking position and the operative movement of the actuating lever 3 can be completed. The complete movement of the lever 3 is arrested by the engagement of the lug 17 on the said lever 3 with a stop shoulder 26 formed upon the forward edge of the bracket 2.

The coin chute C is comprised of a back plate 27 and a front cover plate 28 in which the coin slot 29 is formed, the said cover plate 28 being fixed to the rear plate 27 by means of the screws 30. The coin chute is fixed to the upper end of the bracket 2 by screws 31 which have threaded engagement with tapped orifices in the lugs 32 integral with the front plate 28. The coin chute C extends upwardly from the bracket 2 through the top of the casing 1, the upper end of the cover plate 28 being laterally off-set and is provided with an opening 33 through which the coins are inserted.

A coin retaining latch 35 illustrated clearly in Fig. 7 is pivotally secured to a lug 36 on the front cover plate 28 of the coin chute C, the body portion of which extends upwardly into a slot 37 in the front cover plate 28. A laterally extending stop 39 at the upper end of the latch 35 extends into the cutout portion of notch 40 in the back plate 27 of the coin chute C and partially projects into the right hand portion of the coin slot 28 with respect to Fig. 3. A spring 41, the ends of which are secured respectively to an arm 42 of the latch 35 and a lug 43 on the rear plate 27 holds the latch 35 in its normal position with

the stop 39 partly extending into the coin slot 29 of the coin chute.

The insertion of a coin in the opening 33 will pass through the coin slot 29 and will be arrested in operative position in the coin slot, by the stop 39 of the latch 35 as indicated at "a" in Figs. 3 and 6. The deposited coin lies in front of the forward end of the plunger 24 and will arrest the movement of the same as described and prevent the movement of the latch 12 to its locking position so that the actuating lever 3 can be completely operated. The release of the coin as indicated at "a" is under the control of a lever 45 provided with a substantially vertical portion 46 and an intermediate portion 47 formed at right angles thereto and a substantially vertical, upwardly extending portion 48 which extends parallel with the coin chute C but forward of the same. The lever 45 is pivotally secured intermediate of its ends by a pivot pin 49 secured to the bracket 2 and its lower end is provided with a slot 50 having a substantially vertical portion 51 and an angular off-set portion 52. A pin 53 extends through the slot 50 and is in turn secured to the actuating lever 3 which when depressed causes the pin 53 to move down through the vertical portion of the slot and its entrance into the angular portion 52 causes the lever 45 to be moved about its pivot, causing the upper end 48 which is forward of the coin chute C to move toward the same. The upper end of the lever 45 carries a plunger or finger 55 which is adjustably secured thereto by a set screw 56 and this movement of the upper end of the lever 45 now moves the finger 55 into engagement with the face of an integrally formed angularly extending arm 57 of the latch 35 which lies forward of the coin chute C and parallel thereto to move the latch 35 about its pivot against the tension of the spring 41. The stop 39 is now moved from the coin chute 29 and from the path of the arrested coin to permit the same to drop into a suitable receptacle. The vertical portion 51 of the slot 50 in the lower end of the lever 45 permits movement of the lever 3 when the same is depressed without inserting a coin as before described, without affecting the movement of the latch 35.

Difficulty has been experienced in coin chutes of this character in that a subsequent spurious token of a diameter to be received by the coin slot but very much thinner than that of a regular coin or token is inserted before the previously inserted token or coin of the proper kind has operated the mechanism associated with the coin chute, to maliciously render the mechanism inoperative. This token or slug although the same diameter as the proper token or coin to be received by the coin chute is of such thickness that when it has reached the previously inserted token or coin, the contacting edges of the two tokens will overlap with the result that this overlapping condition will cause the thin spurious slug or token to jam in the coin slot and thus render the mechanism inoperative until this jamming condition is removed. To overcome this condition there is provided an automatic trip device which will cause subsequent coins to be thrown or deflected out of the coin slot until the previously inserted coin or token has caused the mechanism to operate, said subsequent insertions of coins or tokens or slugs of the character described above being returned to the depositor.

To this end there is provided on the front plate 28 of the coin chute C a trip member 60 having

a vertically disposed U-shaped body 61, provided with rearwardly extending ears 62 adapted to pivotally support the trip member 60 between a pair of aligned lugs 63 on the front plate 28 by a pivot member 64, having an angular portion 65 engaging a lug 66 on the front plate 28 to retain the pivot 64 in position against displacement. The body portion 61 of the trip member 60 is provided with an integrally formed upwardly extending arm 68, the upper portion of which is bent forward to provide an enlarged end portion 69, at right angles to the main body portion and the said arm 68. This end portion constitutes the coin stop 69 which is adapted to extend into and reciprocate in a slot 70 provided therefor in the front plate 28 of the coin chute C and to further extend across the coin slot 29 between the front and rear plates of the coin chute C. The opening 70 into which the coin stop 69 extends is angularly disposed to a horizontal plane and the stop member 69 is also located in a plane likewise angularly disposed to a horizontal plane, thus providing the stop member 69 with an inclined upper surface.

The depending arm 71 integral with the body 61 of the trip member 60 has secured to it by rivets or other suitable means a leaf spring 72 slightly bowed and constructed of suitable spring material such as phosphore bronze. The free end of the spring 72 extends through vertically aligned slots 73 in the front and rear plates of the coin chute C and the coin slot 29. The trip member 60 is so pivoted that its balance is such that the weight of the lower portion of the same maintains the leaf spring 72, normally extending through slots 73 in the front and back plates of the coin chute C and the stop member 69 at the top of the same, substantially forward of the slot 70.

Upon insertion of a coin or token shown in Fig. 3 and indicated by the character "b" the advancing edge of the descending coin will engage the portion of the leaf spring 72 projecting through the vertical slots in the plates of the coin chute C, forcing the same to the left with reference to Fig. 4. This causes the trip member 60 to move about its pivot 64 to move the inclined coin stop 69 into the slot 70 in the plate 28, forcing the machined edge 75 of the coin stop 69 into contact with the machined portion 76 of the inside face of the rear plate 27 adjacent to the coin stop 69. The bowed leaf spring 72 as the coin continues its downward movement is flexed against its normal tension and as the coin or token comes to rest against the stop 39 of the latch 35 as indicated at "a" in Figs. 3 and 6, the tip of the spring 72 is in engagement with the face of the coin as illustrated in Fig. 4.

The depth of the slot passage 29, as clearly illustrated in Fig. 5, is slightly greater than the thickness of the coin or token that is deposited but with the construction just described the tension of the flexed spring 72 is such as to force the coin or token against the inner face of the rear plate 27 of the coin chute C to firmly but yieldingly hold the edge 75 of the coin stop 69 against the machined surface 76 to prevent any movement of the trip member 60 about its pivot.

Upon a subsequent coin being inserted before the deposited coin has operated the mechanism, it is obvious with reference to Figs. 3 and 4 that the stop member 69 now lying across the coin slot 28 will not only actually stop said subsequently inserted coin, but the inclined upper surface of the member 69 will positively cause the said

coin indicated at "b" to roll sideways out of the slot 29 through the opening 80 in the side of the coin chute C and into a suitable return chute 81 shown dotted in Fig. 3. With the arrangement as above described should a spurious token other than that of the prescribed kind and of a certain thickness be deposited and an attempt to drop another spurious token of the same type into the coin slot 29 to cause the two overlapping tokens thus deposited to jam the coin slot 29 as previously pointed out, the instant that the first token contacts the leaf spring 72 in its downward movement in the coin slot 29, the trip member 60 is moved about its pivot to cause the coin stop 69 to close the coin slot 29 and the arrest of the token by the stop arm 39 of the latch 35 will find the top of the leaf spring 72 in engagement with the face of this deposited slug to force the same against the inside face of the back plate 27 and the tension of the flexed spring 72 is such as to maintain the edge of the coin stop 69 in engagement with the machined portion of the inner face of the back plate 27; thus the subsequent insertion of any token of a similar type is deflected by the inclined face of the coin stop 69 into the conveyor 81. This type of construction as just described eliminates any possibility of jamming the coin slot 29 due to reasons already pointed out.

Referring now to Figs. 8 and 9, there is shown a modified form of trip member 85 associated with the coin chute C previously described. The trip member 85 is secured to the front plate 28 of the coin chute by a pivot which extends through suitable lugs on the plate 28 and rearwardly extending ears on the body portion of the trip member 85 similar to the trip member 60 in Figs. 3 and 4. An upwardly extending arm similar to the arm 68 is also provided with a forwardly bent portion and an enlarged end portion projecting at right angles to the enlarged end portion and this end portion also constitutes a coin stop 69 which extends into a slot 70 as shown in Figs. 8 and 9. The end 69 reciprocates in a slot 70 and further extends across the coin slot 29 into the coin chute, the said slot 70 and coin stop 69 also being angularly disposed to a horizontal plane. The integrally formed depending arm of the trip member 85 is provided with a depending finger 86 which extends through vertically aligned slots 73 in the front and back plates 28 and 27 of the coin chute C. The trip member 85 is so pivoted that its balance is such that the weight of the lower portion maintains the stop member 69 at the top of the same substantially out of the angular slot 70 and the depending finger 86 extending through the vertical slots 73 in the respective plates of the coin chute C to traverse coin slot 29. A bowed leaf spring 90 is secured to the rear face of the back plate 27 of the coin chute C by suitable rivets and extends forwardly through the vertical slots 73 in the respective front and rear plates of the coin chute C, as indicated in dotted lines in Fig. 9. The leaf spring 90 extends through the slots to the left of the depending finger of the trip member with reference to Fig. 8 and also traverses a portion of the coin slot 29. The spring 90 and depending finger 86 extending through the vertical slots 73 in the respective plates of coin chute C in opposite directions, thus cross each other but do not touch, to form a crotch which lies substantially in the coin slot 29. Upon the insertion of a coin, as shown in Fig. 8, the advancing edge of the descending coin will engage the crotch formed by the oppositely ex-

tending spring 90 and depending finger 86 and the continued downward movement of the coin will force the spring 90 and depending finger 86 in opposite directions. The movement of the depending finger 86 causes the trip member 85 to move about its pivot to move the inclined stop 69 into the slot 70 in the top plate of the coin chute, forcing the edge of the coin stop 69 into engagement with a machined portion of the inner face 10 of the rear plate of the coin chute adjacent to the coin stop, thus bridging the same across the coin slot 29. The finger 86, when the coin is in its arrested position engaging the stop 39 of the latch 35, engages the front face of the coin with 15 respect to Fig. 9 and the tip of the spring 90 in turn engaging the rear face of the coin. The tension of the flexed spring 90 is such as to force the face of the coin resting in the coin slot 29 into engagement with the inside face of the front 20 plate of the coin chute and as the finger 86 engages this face of the coin, the coin stop 69 is pressed firmly into engagement with the inner face of the back plate of the coin chute to prevent any movement of the operated trip member 25 85.

It is readily apparent from the above description that if a slug other than a coin or token of the prescribed kind and also much thinner is inserted into the coin slot, the same, when arrested by the stop arm 39 of the latch plate 35, is forced against the inner face of the front plate of the coin chute by the spring 90 which also moves the finger 86, as is readily apparent, to maintain the edge of the inclined stop 69 against 30 the machined inner face of the rear plate of the coin chute C. The spring 90, although independent of the trip member 85, serves the same purpose of the spring 72 of Figs. 3 and 4 and in association with the depending finger 86 on the trip member 85 provides means to allow the trip member 85 to adjust its upper inclined coin stop 69 with the inner face of the rear plate of the coin chute so that after a coin has been deposited in the coin slot, and is positioned in the 40 lower portion of the coin slot, whether of the prescribed kind or a slug for the purpose of maliciously jamming the same is inserted, any subsequent coin in the coin slot will be deflected by the inclined face of the coin stop 69 through the 45 opening in the side of the coin chute as before described.

In Figs. 10 and 11 is shown another modified form of trip member 95, in which the upwardly extending arm of the same is in the form of a resilient member 96 and is secured to an integrally formed upwardly projecting portion 97 by means of suitable rivets. The member 96 is provided with an enlarged end portion which is bent forward at right angles to the body of the same 55 and also at an angle to a horizontal plane. This angular portion is adapted to extend into and reciprocate in a slot 70 which is also angularly disposed to horizontal plane and when in actuated position extends into the coin slot to form a coin stop. The trip member 95 is also provided with a depending finger 98 of the same form as described 60 in connection with Figs. 8 and 9. When a coin is deposited in the coin slot 29 of the coin chute C, the descending coin engages the finger 98 to 65 move the trip member 95 about its pivot to move the coin stop 99 into the slot 70 to bridge the same across the said coin slot. In this position the edge of the coin stop 99 is in engagement with the machine's inner face of the back plate 27. The 70 descent of the coin is arrested by the stop 39 on

the latch 35 as previously described and when in this position the tip of the finger 98 is in engagement with the exposed face of the coin through the vertical slot 73 in the front plate 28. The shift of the finger 98, due to the descending coin, 75 forces the coin stop 99 into engagement with the plate 27, causing the resilient member 96 to be flexed. Due to this flexure of the member 96 the coin or token which is engaged by the finger 98 is forced against the inside face of the back plate 27 and held in this position under the tension of the member 96, and with the coin stop 99 in positive engagement with the inside face of the back plate 27, thus any subsequent coin whether 80 of the prescribed kind or a slug for the purpose of maliciously jamming the same, is inserted into the coin slot, it will be deflected by the inclined face of the coin stop 99 through the opening in the side of the coin chute as previously described.

Having thus described the preferred embodiment of my invention, what I claim and desire to secure by United States Letters Patent is:

1. In a machine of the class described, a coin chute, mechanism controlled by a coin deposited in said chute, and tiltable means for closing said coin chute to the passage of a second coin until after the said mechanism has operated under the control of said deposited coin, comprising a movable member having a head projectable into said coin chute and engageable with the wall thereof, and spring means engageable by said deposited coin for actuating said member to move said head into said coin chute, said spring means being adapted resiliently to hold said head in blocking position in said chute against a wall thereof to close the same.

2. In a machine of the class described, a coin chute, mechanism controlled by a coin deposited in said chute, a coin stop yieldingly held in blocking position in said chute against a wall thereof for closing said chute to the passage of a second coin until after said mechanism has operated under the control of said deposited coin, and spring means actuated by said deposited coin for moving said stop into blocking position and 110 yieldingly holding said stop against a wall of said chute.

3. In a machine of the class described, a coin chute, mechanism controlled by a coin deposited in said chute, a pivoted lever, resilient means associated with said lever engaged by said deposited coin to project and resiliently hold said lever across said chute against a wall thereof to close said chute to the passage of a second coin until after said mechanism has operated under the control of said first coin.

4. In a coin control apparatus, the combination of a coin chute, a coin return chute, a trip device pivotally secured to said coin chute, an upwardly extending arm integral with said trip device; a flared end portion for said arm bent rearwardly and formed with an inclined face, an inclined slot in the said coin chute in which said inclined bent portion reciprocates, resilient means secured to said trip member extending downwardly and rearwardly into a vertical slot and transverse of said chute, the resilient means being engaged by a coin inserted in said coin chute to tilt said trip member and move said inclined bent portion in the said inclined slot to yieldingly hold the same bridged across the said coin chute against a wall thereof whereby a subsequently inserted coin is stopped and caused to roll from said inclined surface into said coin return chute.

5. In a coin control apparatus the combination

of a coin chute, a coin return chute, a trip device pivotally secured to said coin chute, an upwardly extending arm integral with said trip device, a flared end portion of said arm bent rearwardly and formed with an inclined face, a slot in said coin chute in which said inclined bent portion reciprocates, a resilient leaf spring secured to said trip member extending downwardly and rearwardly into a vertical slot which merges with said coin chute to permit said depending spring to bridge a portion of said coin chute, the descending coin in said coin chute being adapted to be engaged by said bridging spring to force the same out of said coin chute to tilt said trip member to move the inclined portion of said arm into said slot and into engagement with the wall of said coin chute, to bridge the same and yieldingly hold said bent inclined portion in engagement with said wall of said coin chute whereby a subsequently inserted coin is stopped and caused to roll from said inclined surface into said return chute.

6. In a coin control apparatus, the combination of a coin chute, a coin return chute, a trip member pivotally secured to said coin chute, an upwardly extending arm integral with said trip device, a flared end portion for said arm bent rearwardly and formed with an inclined surface, an inclined slot in said chute in which said inclined bent portion reciprocates, resilient means secured to said trip member extending downwardly and rearwardly through a vertical slot in said coin chute and into said coin chute therein, said spring being adapted to engage a coin inserted in said coin chute to tilt said trip device to move said inclined bent portion through said inclined slot into said coin chute, to yieldingly hold the same bridged across the coin chute and in engagement with the wall of said coin chute irrespective of the thickness of the inserted coin whereby a subsequently inserted coin is stopped and caused to roll from said inclined surface into said coin return chute.

7. In a coin controlled apparatus, the combination of a coin chute, a coin return chute, a trip member pivotally secured to said coin chute, an upwardly extending arm integral with said trip member, a flared end portion for said arm bent rearwardly and formed with an inclined face and an inclined slot in said chute in which said inclined bent portion reciprocates, a depending rearwardly extending finger integral with said trip member extending through a vertical slot in the face of the coin chute and into said coin chute, a resilient member secured to the rear face of said coin chute also extending through a slot in the rear face of the coin chute and into said coin chute, said resilient means and said finger engaging an inserted coin, said engaged finger tilting said trip member to move said inclined end portion through said inclined slot into the said coin chute to bridge the same, said resilient means maintaining said inclined portion of the trip member in yielding engagement with the wall of the said coin chute and whereby a subsequently inserted coin is stopped and caused to roll from said inclined surface into said coin return chute.

70

8. In a coin control apparatus the combination of a coin chute, a coin return chute, a trip member pivotally secured to said coin chute, an upwardly extending arm integral with said trip member, a flared end portion for said arm extending rearwardly and formed with an inclined face and an inclined slot in said chute in which said inclined portion of said arm reciprocates, a depending rearwardly extending finger integral with said trip member, extending through a vertical slot in the face of the coin chute and into said coin chute, a resilient member secured to the rear of said coin chute also extending through a slot in the rear face of the coin chute and into said coin chute, said resilient means and said finger engaging an inserted coin, said engaged finger tilting said trip member to move said inclined portion through its associate slot into said coin chute to bridge the same, said resilient means engaging said inserted coin to positively hold the same in engagement with said finger to yieldingly hold the inclined end portion of the said trip member across the said coin slot in engagement with the wall of said coin chute irrespective of the thickness of the inserted coin and whereby a subsequently inserted coin is stopped and caused to roll from said inclined surface into said coin return chute.

9. In a coin control apparatus the combination of a coin chute, a coin return chute, a trip device pivotally secured to said coin chute, an upwardly extending resilient arm secured to said trip member, a flared end portion of said resilient arm bent rearwardly and formed with an inclined face, an inclined slot in said chute in which said inclined bent portion of said resilient arm reciprocates, a depending finger integral with said trip member extending through a vertical slot in a coin chute engaging a coin inserted in said coin chute, to tilt said trip member to move said inclined bent portion of said resilient arm through said inclined slot into said coin chute and in engagement with the wall of the coin slot to bridge the same, said resilient means maintaining said finger positively in engagement with said deposited coin to permit a positive engagement of said flare end with the said coin slot wall and whereby a subsequently deposited coin is stopped and caused to roll from said inclined surface of said resilient arm into said coin return chute.

10. In a coin control apparatus, the combination of a coin chute, a coin return chute, mechanism controlled by a coin deposited in said chute, and tiltable resilient means affected by said deposited coin and projected in said coin chute by said deposited coin for closing said chute to the passage of subsequently deposited coins and deflecting said subsequent coin into said return chute until after said mechanism has operated under the control of said first coin, said resilient means cooperating with said coin chute and any coin deposited therein to compensate automatically for manufacturing variations in the dimensions of said chute and for variations in the thicknesses of the coins deposited therein.

CHARLES B. GILMORE.
